PIPE-CLEANER.

1,099,541.

Specification of Letters Patent. Patented June 9, 1914.

Application filed August 6, 1913. Serial No. 783,349.

To all whom it may concern:

Be it known that I, ALBIN C. EEK, a citizen of the United States, residing at the city of Webster Groves, in the county of St. Louis and State of Missouri, have invented 5 certain new and useful Improvements in Pipe-Cleaners, of which the following is a specification.

This invention relates to pipe cleaning devices, and contemplates the provision of novel improvements of the pipe cleaning device that constitutes the subject-matter of the application of Henry W. Lee, Serial No. 754,174, filed March 14, 1913.

15 One of the objects of the present invention resides in the provision of a device of the character described having automatically adjustable means for preventing rotary movement of the drum-support.

20 Another object of the present invention resides in the provision of means for locking the automatically adjustable means for preventing rotary movement of the drum-support in operative relation with respect to 25 the drum, which locking means, when actuated to release the drum-support, permits the setting of the automatically adjustable means for preventing rotary movement of the drum-support in inoperative relation 30 with respect to the drum for convenience in mounting the drum upon or removing same from a pipe.

Another object of the present invention consists in the provision of novel means for 35 supporting and holding the scale-removing means in engagement with the periphery of the pipe being cleaned.

40 A further object of the present invention consists in the provision of improved means for closing and locking the parts of the drum around a pipe.

Further, the present invention consists in the provision of an adjustable bracket for preventing rotary movement of the drum-support.

45 With these and minor objects in view, the present invention consists of the novel features of construction and arrangement of parts hereinafter more fully described and 50 pointed out in the claims.

In the accompanying drawings forming part of this specification, in which like numbers of reference denote like parts wher-

ever they occur, Figure 1 is a front view of a pipe cleaner embodying the present invention, showing same mounted on a pipe to be cleaned; Fig. 2 is a sectional view on the line 2—2, Fig. 1; Fig. 3 is a sectional view on the line 3—3, Fig. 1; Fig. 4 is an end elevation of the drum, showing same partly closed around a pipe to be cleaned; Fig. 5 is a similar view showing the drum completely closed around the pipe; Fig. 6 is perspective view on an enlarged scale of a center-supporting pin; Fig. 7 is a detailed view 65 of one of the drum closing and locking devices; Fig. 8 is an end elevation of the drum mounted on a pipe to be cleaned and having an alternate form of the means for preventing rotary movement of the drum-support; Fig. 9 is a sectional view on the line 9—9, Fig. 8; Fig. 10 is a sectional view on the line 10—10, Fig. 8; Fig. 11 is a sectional view on the line 11—11, Fig. 8; Fig. 12 is a 70 sectional view on the line 12—12, Fig. 8; Fig. 13 is a sectional view on the line 13—13, Fig. 9; Fig. 14 is an elevation of the adjustable crank; and Fig. 15 is a sectional view on the line 15—15, Fig. 14.

The drum 1 comprises two semi- or nearly 80 semi-cylindrical members 2 and 3, which are preferably hinged together adjacent to the ends thereof by means of bolts 4 or the like, so that the drum can be readily placed around a pipe 5 to be cleaned and as readily 85 removed from the pipe after the cleaning operation. The free side of the member 2 has relatively deep recesses or notches 6 formed therein adjacent to the ends of same, there being a pin or bolt 7 located in each recess or notch 6 and supported in openings in the side walls of same. Openings 8 are formed in the member 3 adjacent to the free side thereof, which openings register in circumferential alinement with the recesses 6, 90 respectively, in the member 3 when the drum is closed, and have hooks 9 supported therein for engagement with the pins 7, respectively. Each hook 9 is preferably provided with a bifurcated end, the prongs 10 of which extend into an opening 8 in the member 3 and contain openings to receive a pin 11, which has its ends supported in slots 12 in the side walls 13 of said opening 8. A lever 14, which is mounted on the pin 11 intermediate the 100 prongs 10 of the hook 9, bears an extension 105

or arm 15 for engagement with a wear-iron 16, which may be secured in a groove 17 in the end wall 18 of the opening 8, as shown in Figs. 4, 5, and 7. When the handle of the lever 14 is moved outwardly from the member 3, the extension 15 moves inwardly away from the wear-iron 16 and thereby permits the pin 11 to be moved toward the end wall 18 of the opening 8, whereupon the free end of the hook 9 can be moved inwardly to catch upon the pin 7 in a recess 6 in the member 2, when the drum 1 is nearly closed around a pipe 5, as shown in Fig. 4. The handle of the lever 14 is then moved inwardly toward the member 3 whereby the extension 15 of said lever presses against the wear-iron 16 and thereby forces the pin 11 away from the end wall 18 of the opening 8, with the result of causing the hook 9 to draw the free sides of the members 2 and 3 together, so as to close the drum completely around the pipe 5, as depicted in Fig. 5. When the lever 14 is moved to the position to cause the hook 9 to close the drum 1 as just described, the handle of said lever lies in a depression 19 in the outer surface of the member 3, so as to be flush or nearly flush with the outer surface of said member, and the hook 9 extends through a cut-away portion 20 in the end wall 18 of the opening 8, so as to be flush or nearly flush with the outer surfaces of the members 3 and 2. It will be observed that, when the lever 14 occupies the position to cause the hook 9 to lock the free sides of the members 2 and 3 together, the extension 15 of said lever engages the wear-iron 16 at a point outside the line through the axes of the pins 7 and 11, as best seen in Fig. 5, whereby the tendency of the free sides of the members 2 and 3 to move apart holds said lever in its locking position. In order to unlock the free sides of the members 2 and 3, the handle of each lever 14 is withdrawn from its depression 19 in the member 3, so as to move the extension 15 of each lever 14 inwardly away from its wear-iron 16, after which the hooks 9 can be detached from the pins 11 in an obvious manner.

50 The members 2 and 3 bear semi- or nearly semi-annular ribs 21, which are located on the outer surfaces of same adjacent to the ends thereof, each rib 21 containing an opening 22 or a plurality of such openings and, also, the usual scale-discharging opening or openings 23. Each opening 22 receives a cleaning device, by means of which the scale or other formation or accumulation on the outer surface of the pipes 5 is removed. By preference, each cleaning device consists of a pair of cutters 24, which cutters are revolvably mounted on a pin 25, though, if desired, each pin may have only one cutter or three or more cutters revolvably mounted

thereon. The end portions of the pin 25 rest 65 in relatively deep notches 26, respectively, in the outer surface of the rib 21 adjacent to the side walls of the opening 22 and have their opposite sides flattened as at 27 to fit closely to the sides of the notches 26, so as to 70 prevent rotary movement of said pin, being retained in place in said notches by the ends of the spring-arms 28 of a plate 29. Said plate 29 is supported in a depression 30 in the outer surface of the rib 21, so as to be 75 flush or nearly flush with the outer surface of said rib, and may be held in place in said depression by a screw 31 or a plurality of such screws and a dowel-pin 32. The spring-arms 28 of the plate 29 press the ends of the 80 pin 25 toward the bottoms of the notches 26 and thereby causes the cutters 24 to exert pressure upon the periphery of the pipe 5 in order to cut the scale, etc., on the pipe.

It will be observed that each pin 25 is disposed so that its axis extends at an acute angle to a plane perpendicular to the axis of the drum for the purpose described in the above-mentioned application.

The drum 1 is rotated by means of the 90 following mechanism: A pair of ribs 33 borne by the member 2 register in circumferential alinement with a pair of ribs 33, respectively, borne by member 3. Said ribs 33 are spaced apart from the ribs 21, and one 95 of the ribs 33 on member 2 bears gear-teeth 34, which register in circular alinement with gear-teeth 34 on its complementary rib 33 on member 3. Said gear-teeth 34 are preferably beveled, and mesh with a beveled pinion 35, which is rigidly mounted on the inner end of a shaft 36, the latter being journaled in a hollow boss 37 borne by a supporting member 38 and being preferably disposed at substantially a right-angle to the 105 axis of the drum 1. The outer end of the shaft 36 projects from the outer end of the boss 37 and bears a crank-handle 39, by means of which the former is rotated to impart rotary movement to the drum 1 110 through the medium of the pinion 35 and the gear-teeth 34. The member 38 extends longitudinally of the drum 1 from opposite sides of the shaft 36, and each end of said member bears a yoke 40 having a semi- or 115 nearly semi-annular groove 41 or a plurality of such grooves in its inner face, one of the yokes 40 being adapted to straddle the drum 1 intermediate the ribs 21 and 33 near one end of the drum, and the other yoke 40 120 being adapted to straddle said drum intermediate the ribs 21 and 33 near the other end of the drum. Each groove 41 is preferably T-shaped in cross-sectional configuration, and receives circularly-alining ribs 42 borne 125 by members 2 and 3, said ribs 42 being adapted to travel through said groove and, also, being T-shaped in cross-sectional con-

figuration so as to be retained in said grooves, as best seen in Fig. 2. By this arrangement, the yokes 40 support the drum 1 and allow the latter to be rotated.

5 In order to prevent the member 38 from rotating around the drum 1, when the shaft 36 is rotated, a member 43 is supported by the boss 37, which extends through an opening in an enlarged portion 44 of the member 10 43, said enlargement being substantially equidistant from the ends of the latter and being relatively shorter than the boss 37. Each end of the member 43 is reduced to form a pintle 45 on which a roller 46 is rev- 15 olably mounted, each roller 46 being preferably relatively wide and being held in place on its pintle 45 by a washer 47 and a cotter-pin 48 or other suitable means. The rollers 46 are located at such distances from the 20 drum 1 and are of such size in diameter that, when the drum 1 is mounted on a pipe 5 to be cleaned and the member 43 is held in a position at substantially a right-angle to the axis of the drum 1 as hereinafter de- 25 scribed, each roller 46 will stand in position to engage the periphery of or the scale, etc., on a pipe 5 adjacent to the pipe being cleaned, whereby the pipe or pipes adjacent to the pipe being cleaned will prevent the 30 member 38 from rotating around the drum, the result being that the drum is caused to rotate around the pipe to be cleaned, when the shaft 36 is rotated. The member 43 is mounted on the boss 37, so that it can be 35 reciprocated longitudinally of the latter, and is held normally in a position at substantially a right-angle to the axis of the drum 1 by means of a bolt 49, which is supported in an opening 50 in the enlargement 44 of the member 43 and is pressed toward the boss 37 by a spring 51, so that its inner end projects into a longitudinal groove 52 in said boss 37. The outer end of the bolt 49 is 40 preferably reduced, and extends through an aperture 53 in the outer wall of the opening 50, a button or knob 54 being secured to same to afford a means by which the bolt can be pulled outwardly to withdraw the inner end of said bolt from the groove 52, so that the 45 member 43 can be rotated on the boss 37 to a position parallel or nearly parallel to the drum 1 for convenience in mounting the drum on a pipe 5 or removing the drum from the pipe. A spring 55, which is inter- 50 posed between the outer end of the enlargement 44 of member 43 and the handle 39, presses the member 43 toward the drum, so as to hold the rollers 46 in engagement with the pipes 5 or the scale, etc., on said pipes 55 adjacent to the pipe being cleaned. By this arrangement, the member 43 is free to move 60 away from the drum, in case a roller 46 rides over a bump on a pipe adjacent to the pipe being cleaned and, also, in case the pipe

being cleaned is farther away from the axis 65 of the rollers 46 than the pipes on which said rollers ride.

In the alternate form of the invention depicted in Figs. 8 to 15, inclusive, the member 43 is omitted entirely and in lieu thereof the following adjustable means for preventing rotary movement of the member 38 is provided. The member 38 is somewhat modified, being provided with a central enlarged portion 56 having a vertically disposed recess or relatively wide groove 57 in its outer face to receive a plate 58, which contains a vertical slot 59, through which the boss 37 extends. The sides of the plate 58 fit closely to the side walls of the recess or groove 57 and thereby prevent rotary movement of said plate as long as same remains in said recess or groove. The thumb-nut 60, which fits on the boss 37 and has an internally screw-threaded portion for engagement with an exteriorly screw-threaded portion of the boss 37, affords a means for holding the plate 58 stationary in the recess or groove 57. The plate 58 bears a hollow boss 61 for the reception of a pin 62 borne 90 by the end of the arm 63 of an L-shaped member 64, said boss 61 being preferably arranged to extend rearwardly from one end of the plate 58. A tongue 65 projects from the front side of the plate 58 into a groove 95 66 in the rear side of an enlargement 67 on the end of the arm 63 of member 64, so as to prevent rotary movement of the member 64. The pin 62 is locked in place in the boss 61 by means of a bolt 68, which is supported in an opening 69 in the boss 61 and is pressed inwardly by a spring 70, so that the inner end of said bolt projects into an opening 71 in the pin 62, the outer end of said bolt being preferably reduced to extend through an aperture 72 in the outer wall of the opening 69 and bearing a button or knob 73 by means of which the bolt 68 can be drawn outwardly to withdraw the inner end of the latter from the opening 71, so as 100 to allow the member 64 to be detached from the plate 58 by merely pulling the member 64 forwardly to withdraw the pin 62 from the boss 61. The arm 63 of the member 64 extends substantially perpendicular to the 105 axis of the shaft 36, and the other arm 74 of said member extends rearwardly in substantially parallel relation to the axis of the shaft 36 so as to extend between two pipes 5 adjacent to the pipe 5 on which the drum may be mounted, as best seen in Fig. 8. The arm 74 of member 64 has a pintle 75 secured in an opening 76 therein near the arm 63 by means of a set-screw 77 or the like and, also, has a pintle 78 detachably supported in an opening 79 therein adjacent to the rear end thereof by means of a spring-controlled bolt 68', which is like the bolt 110 115 120 125

68 hereinabove described and is provided on its outer end with a button 73'. Rollers 80 and 81 revolvably mounted on the pintles 75 and 78 are held in place thereon by washers 82 and cotter-pins 83 or other suitable means and are adapted for engagement with the front and rear sides, respectively, of a pipe 5 adjacent to the pipe being cleaned, so as to prevent rotary movement of the members 38 and 64.

10 It will be evident that when the thumb-nut 60 is loosened, the plate 58 can be slid upwardly or downwardly to raise or lower the member 64, so as to adjust the position 15 of the arm 74 of the member 64 relative to the axis of the drum for various spacings of pipes 5. Furthermore, by loosening the thumb-nut 60 sufficiently to allow the plate 58 to be withdrawn from the recess or 20 groove 57 in the enlargement 56 of the member 38, the plate 58 can be then manually rotated through substantially 180 degrees to move the member 64 from its position above the member 38 to a position below 25 the latter, after which said plate can be clamped in the recess or groove 57 by tightening the thumb-nut. By reason of the pin 62 being locked in the boss 61 of plate 58 by means of the spring-controlled bolt 63 30 and the pindle 78 being locked in the opening 79 in arm 74 of member 64 by means of the spring-controlled bolt 68' as hereinabove described, these bolts can be actuated to release the pin 62 and pindle 78, so 35 as to allow the member 64 to be detached from the plate 58 and the pindle 78 to be detached from the arm 74 for convenience in mounting the drum on a pipe to be cleaned or removing the drum from a pipe.

40 The crank-handle 84 is preferably formed of two parts 85 and 86, the latter having a longitudinal groove 87, in which the part 86 is held by means of bolts 88, which bolts pass through openings in the part 86 and a longitudinal slot 89 in the part 85, so that the crank-handle can be lengthened or shortened in an obvious manner. The part 86 of the crank-handle 84 is revolvably mounted on a collar 90, which is rigidly mounted 45 on the shaft 36 adjacent to the outer end of same, and is held in place on the collar 90 by an annular flange 91 on the latter and, also, a washer 92 and a nut 93, which is secured to the outer end of said shaft. A 50 pawl 94, which is supported in an opening 95 in the part 86 of the crank-handle 84, is controlled by a spring 96 to coöperate with ratchet-teeth 97 on the collar 90, so as to allow the shaft 36 to be rotated by oscillatory movement of the crank-handle 84 when it is impossible to impart complete rotary movement to said crank-handle.

I claim:

1. A pipe cleaner including a revolv-

65 cleaning means adapted to encircle the pipe, means for rotatably supporting said cleaning means, means borne by said supporting means for rotating said cleaning means, and means adjustably supported by said supporting means so as to be capable of swinging movement toward and away from a support to hold said supporting means against rotation.

70 2. A pipe cleaner including a revolvble cleaning means adapted to encircle the pipe, means for rotatably supporting said cleaning means, means borne by said supporting means for rotating said cleaning means, and spring-controlled means supported by said supporting means adapted for engagement with a support to hold said supporting means against rotation.

75 3. A pipe cleaner including a revolvble cleaning means adapted to encircle the pipe, means for rotatably supporting said cleaning means, means borne by said supporting means for rotating said cleaning means, spring-controlled means supported by said supporting means adapted for engagement with a support to hold said supporting means against rotation, and releasable means for locking said spring-controlled means in operative relation with respect to the support.

80 4. A pipe cleaner including a revolvble drum adapted to encircle the pipe and having cleaning means, a member adapted to rotatably support said drum and having an extension, means carried by said member so as to be capable of being rotated relative 85 thereto and for rotating said drum, and means supported by the extension on said member adapted for movement into and out of engagement with a support to hold said member against rotation.

85 5. A pipe cleaner including a revolvble drum adapted to encircle the pipe and having cleaning means, a member adapted to rotatably support said drum and having an extension, means carried by said member for 90 rotating said drum, and spring-controlled means supported by the extension on said member adapted for engagement with a support to hold said member against rotation.

95 6. In a pipe cleaner including a revolvble drum adapted to encircle the pipe and having cleaning means, a member adapted to rotatably support said drum and having an extension, means carried by said member for 100 rotating said drum, spring controlled means supported by the extension on said member adapted for engagement with a support to hold said member against rotation, and releasable means for locking said spring - controlled means against rotation on the extension on said member.

105 7. A pipe cleaner including a revolvble

- drum adapted to encircle the pipe and having cleaning means, a member adapted to rotatably support said drum and having a hollow extension, means revolubly supported in said extension for rotating said drum, and a spring-controlled element supported by said extension and having means for engagement with a support to hold said member against rotation.
- 10 8. A pipe cleaner including a revoluble drum adapted to encircle the pipe and having cleaning means, a member adapted to rotatably support said drum and having a hollow extension, means revolubly supported in said extension for rotating said drum, a spring-controlled element supported by said extension, and a roller carried by said element adapted for engagement with a support to hold said member against rotation.
- 15 9. A pipe cleaner including a revoluble drum adapted to encircle the pipe and having cleaning means, a member adapted to rotatably support said drum and having a hollow extension, means revolubly supported in said extension for rotating said drum, a spring-controlled element supported by said extension, a roller carried by said element adapted for engagement with a support to hold said member against rotation, and means for locking said element against rotation on said extension.
- 20 10. A pipe cleaner including revoluble cleaning means adapted to encircle the pipe, means adapted to rotatably support said cleaning means, means carried by said supporting means for rotating said cleaning means, a member adjustably secured to said supporting means so as to be capable of being swung toward and away from a support, and means carried by said member adapted for engagement with the support to hold said supporting means against rotation.
- 25 11. A pipe cleaner including a cleaning means carrier adapted to encircle the pipe, means to revolubly support said carrier, and means capable of rotation connected to the supporting means and adapted for movement into and out of engagement with a stationary support to hold the supporting means against rotation.
- 30 12. A pipe cleaner including a cleaning means carrier adapted to encircle the pipe, means to revolubly support said carrier, and means capable of rotation connected to the supporting means and adapted for movement into and out of engagement with a plurality of spaced stationary points to hold the supporting means against rotation.
- 35 13. A pipe cleaner including a cleaning means carrier adapted to encircle the pipe, means to revolubly support said carrier, a projection on said supporting means, pipe engaging means mounted on said projection so as to be capable of manual rotation relative thereto to thereby be moved into and out of engagement with the pipe that said last named means engages, and displaceable means to positively hold said pipe engaging means against rotation relative to said projection.
- 40 14. A pipe cleaner including a cleaning means carrier adapted to encircle the pipe, means to revolubly support said carrier, a hollow extension on said supporting means, pipe engaging means rotatably and longitudinally movable on said extension, releasable means to positively hold the pipe engaging means against rotation, but to allow same to have longitudinal movement relative to the extension, a shaft passed through the hollow extension, means on the inner end of the shaft to rotate the carrier, means on the outer end of the shaft for rotating the latter, and a spring between the pipe engaging means and the shaft rotating means.
- 45 15. A pipe cleaner including a cleaning means carrier adapted to encircle the pipe, means to revolubly support said carrier, a hollow extension on said supporting means, pipe engaging means rotatably and longitudinally movable on said extension, releasable means to positively hold the pipe engaging means against rotation, a shaft passed through the hollow extension, means on the inner end of the shaft to actuate the carrier, and means on the outer end of the shaft to actuate the latter.
- 50 16. A pipe cleaner including a cleaning means carrier adapted to encircle the pipe, means to revolubly support said carrier, an extension on said supporting means, and pipe engaging means mounted on the extension so as to be capable of rotation relative to the extension and also capable of movement longitudinally of the extension.
- 55 17. A pipe cleaner including a cleaning means carrier adapted to encircle the pipe, means to revolubly support said carrier, and spring controlled means adapted to be resiliently held in engagement with a relatively stationary support to prevent movement of the supporting means.
- 60 18. A pipe cleaner including a cleaning means carrier adapted to encircle the pipe, means to revolubly support said carrier, spring controlled means adapted to be resiliently held in engagement with a relatively stationary support to prevent movement of the supporting means, said spring controlled means being capable of manual rotation, and displaceable means to hold the spring controlled means against rotation.
- 65 19. A pipe cleaner including a cleaning means carrier adapted to encircle the pipe, means to revolubly support said carrier, means carried by the supporting means to engage a stationary support to hold the supporting means against rotation, means

whereby the stationary support engaging means may have movement relative to the stationary support so as to permit same to be applied to and removed from the pipe, and means to hold the stationary support engaging means against movement relative to said stationary support.

In testimony whereof I hereunto affix my signature in the presence of two witnesses.

ALBIN C. EEK.
